UNITED STATES PATENT OFFICE.

WILLIAM C. BRAY, OF NEWTON, MASSACHUSETTS.

DESIGN FOR A RIVET.

SPECIFICATION forming part of Design No. 27,567, dated August 24, 1897.

Application filed December 2, 1896. Serial No. 614,241. Term of patent 14 years.

To all whom it may concern:

Be it known that I, WILLIAM C. BRAY, of Newton, in the county of Middlesex and State of Massachusetts, have invented and produced a new and original Design for Rivets, of which the following, taken in connection with the accompanying drawings, is a specification.

Figure 1 of the drawings is a plan of a rivet, showing my design. Fig. 2 is an elevation of the same, and Fig. 3 is a central vertical section of the same on line $x x$ on Fig. 1.

The leading feature of my design consists in a rivet having a tubular cylindrical shank and a circular head having a smooth outer edge and a convex upper surface with a representation of a four-pointed star in relief thereon, with the center of the star coinciding with the center of the head and forming a circular convex hub, from which the several points of the star radiate, said points also being rounded transversely, as shown.

In the drawings, a is the rivet-head, having a convex outer surface, a smooth circular outer edge, and a flat inner surface, and having formed upon said outer convex surface a representation of a four-pointed star raised above the convex surface of the main body of the head a , said star being composed of the central circular hub b , the outer surface of which is convex, and the four points $c c$, radiating therefrom and having their outer surfaces rounded transversely, as shown.

What I claim is—

The design for a rivet substantially as here- 35 in shown and described.

In testimony whereof I have signed my name to this specification, in the presence of two subscribing witnesses, on this 28th day of November, A. D. 1896.

WILLIAM C. BRAY.
